CHARLES GREENSLIT, OF CLEVELAND, OHIO, AND ROSCOE ROYAL, OF CHICAGO,
ILLINOIS.

SIGNALING SYSTEM.

1,188,645.

Specification of Letters Patent. Patented June 27, 1916.

Application filed September 11, 1913. Serial No. 789,369.

To all whom it may concern:

Be it known that we, CHARLES GREENSLIT, residing at Cleveland, in the county of Cuyahoga and State of Ohio, and Roscoe 5 ROYAL, residing at Chicago, in the county of Cook and State of Illinois, both citizens of the United States, have invented certain new and useful Improvements in Signaling Systems, of which the following is a full, 10 clear, and exact description, reference being had to the accompanying drawings.

This invention relates to signaling devices and particularly to devices whereby a plurality of signals may be sent over a single 15 wire and may be automatically distributed depending upon the nature of the signals or the condition of the apparatus by means of which the signals are received.

The invention also relates to signaling 20 devices whereby signals originating at different points may be combined, distributed, or transferred to other points in an automatic manner. The need for such a system or device frequently arises in telephone 25 work, for the purpose of connecting one subscriber with another subscriber thereof; as in automatic systems, wherein the selection 30 is performed by a plurality of impulses sent over the subscriber's wire; in manual systems in which an incoming call is routed to different operators depending upon whether 35 they are busy or free; in the automatic selection of trunk lines; in the automatic distribution from trunk lines to individual lines; 40 in the automatic avoidance of defective apparatus; in the annunciation of "busy" lines; in the connection of supervisory lines; and in other places too numerous to mention. Also in the art of signaling generally, 45 whether by lights, bells, or the human voice, it is frequently desirable to operate different devices depending upon the number of successive signals, or to distribute and display those signals depending upon the source of the signal or the annunciation already made 50 by reason of signals previously sent.

The general objects of this invention are, therefore, the provision of new and improved signaling mechanism whereby a plurality 55 of different signals may be sent over a single wire and automatically sorted out at the receiving end; the provision of new and improved signaling mechanism whereby different numbers or characters of impulses transmitted over a single wire may cause

the actuation of different receiving devices; the provision of new and improved signaling mechanism whereby different signals received over a single wire may be delivered to different groups of receiving apparatus 60 depending upon the previous condition of such receiving apparatus; the provision of receiving apparatus actuatable upon the receipt of different characters of impulse to effect different circuit combinations; the 65 provision of signal receiving mechanism of higher and lower groups wherein the indication of higher groups shall be cleared upon changes in indications of higher groups; the provision of electrical signaling 70 mechanism in which the functions of setting the mechanism and of maintaining the same in set condition shall be performed by different circuits; the provision of a new and improved type of relay; the provision of 75 controlling mechanism whereby the operation of the receiving mechanism may be governed to the end that the receiving mechanism may in no case outrun the originating mechanism; while further general objects 80 will become apparent as the description proceeds.

In the drawings accompanying and forming a part of this application we have shown our improved relay and also a specimen circuit 85 illustrating one mode of connecting up a plurality of those relays so as to effect certain combinations and distributions of the signals received by the system. It will be understood, however, that this is shown 90 merely as a suggestion and that this system when extended in any direction (as may be done by the mere duplication of the connection shown) will serve to fulfil the various functions hereinbefore referred to.

In these drawings Figure 1 is a side elevation of a relay constructed in accordance with our invention, the same being shown in unexcited condition; Fig. 2 is a similar view 100 of the same relay showing the position taken by the parts when the same is excited; Fig. 3 is a longitudinal cross sectional view taken through the center of the magnet and spring pile showing the parts in the same position as in Fig. 1; and Fig. 4 is a diagram 105 of a specimen circuit.

Describing the parts by reference characters the relay in its preferred embodiment comprises a wire coil 1 wound upon a core 2 and supported upon a base 3, there being 110

a bracket 4 preferably of soft iron projecting alongside the coil. Pivoted to the end of the bracket is an armature 5 here shown as of right angle shape with one leg overhanging the core and the other lying alongside the bracket, said second leg being arranged to be thrown away from that bracket upon the energizing of the coil.

Secured adjacent to the bracket 4 are a plurality of parallel resilient spring fingers *a*, *b*, *c*, *d*, *e*, *f*, mounted in the order shown and spaced apart by means of insulation as shown. The free end of the spring *a* overhangs the end of the armature 5 and is formed for contact with the free end of the spring *c*, but is normally spaced therefrom to leave an open circuit. The free end of the spring *b* carries a contact normally engaging the spring *c*. Also the free end of the spring *e* normally contacts with spring *d* but is arranged when displaced to contact with spring *f*. Spring *b* is braced by an insulating post 6, here shown as passing through an aperture in spring *a*, while spring *d* is also braced by an insulating post 7 passing loosely through apertures in springs *a*, *b* and *c* (see Fig. 3). Also a suitable insulating spacing member 8 is introduced between springs *c* and *e* so that upon the displacement of *c* to open the contact *b*—*c*, the spring *e* will also be displaced to open the contact *d*—*e* and close the contact *e*—*f*.

Accordingly during the time that the relay is not energized (Fig. 1) the contacts *b*—*c* and *d*—*e* are closed and the contacts *a*—*c* and *e*—*f* are open. Likewise upon the energizing of the relay these contacts *b*—*c* and *d*—*e* are opened and the contacts *a*—*c* and *e*—*f* are closed. Also it will be seen that upon the attraction of the armature 56 the changes in the relations of the contacts will be performed in a strictly timed manner, the first being the making of the connection at *a*—*c*, next the breaking of the contact *b*—*c*, then the breaking of the contact *d*—*e*, finally making of the contact *e*—*f*; and that upon the release of the armature the changes occur in exactly reversed order.

Certain modes of connecting these relays together and employing them in the circuit are shown diagrammatically in Fig. 4 in which all of the relays are intended to be of the type illustrated in Fig. 1, although shown in conventional form. The various springs are indicated by the same characters as are employed in Figs. 1, 2 and 3, the armature however being omitted and its place being taken by the spring *a*. The various parts will be referred to by the figure of the relay together with the letter of that part.

The battery is shown at 10 (plus and minus being indicated for purposes of clearness of description but not necessary in op-

eration), one side of the battery (here positive) being connected to a main lead 66.

The relays are illustrated as connected in groups, relays 50, 51 and 52 comprising the first or B group; 53 and 54 the second or A group; 55, 56, and 57 the third or C group; 58, 59, and 60 the fourth or D group; and 61, 62, and 63 the fifth or E group. Of course other groups could be employed as desired and connected to each other and to the circuit by any of the modes herein disclosed, but the arrangement here shown is believed to be sufficient to illustrate sufficiently the capabilities of our improved relay.

In the present embodiment we have illustrated the system as controlled by means of a coin drop so that the same may be rendered operative upon the deposit of a coin and may be rendered again inoperative after the occurrence of a predetermined number of operations. While the coin drop may or may not be used, without reference to the remainder of the apparatus, and while it may be employed in connection with any portion of the mechanism, as will be obvious, we have shown it in connection with the main return wire of the system, wherefore an explanation of the same at this point is necessary to an understanding of the apparatus.

The coin chute is shown diagrammatically at 67 and associated therewith is a relay 68 having two armature connections *a* and *b*, both normally open and arranged to close their circuits upon the energizing of the magnet. The relay magnet is connected to the positive main 66 through the supervisory lamp 68¹. Upon the deposit of a coin in the chute contact is made at 67^a causing the passage of current by way of 66, 68¹, 68, 67^a and lead 69 back to the battery. This causes the closing of contacts 68^a and 68^b, 68^a shunting the coin drop so that thereafter current flows from the positive main 66 through lamp 68¹, magnet 68, contact 68^a and return lead 69 whereby the supervisory lamp is continuously lighted. The closing of the contact 68^b completes the circuit through the negative main 70 so as to render operative any mechanism connected thereto. The mode of opening this contact and the effect thereof will be described later. The positive main 66 is also connected to the contact devices 72, 73, 74 and 75, here shown as leading directly from the main 66, although it will be understood that any desired extensions or connections could be interposed therebetween, and that the contacts themselves could consist of receiver hooks, impulse counters, clocks, fire alarm boxes, pilot indicators, target contacts, or even push buttons depending upon the purpose for which the system is to be used. These contacts, when actuated, serve to place the positive 120

main 66 in circuit with wires 76, 77, 78, or 79 respectively as the case may be. The wire 76 is connected with one group of relays which are indicated by A, the wire 77 with the group indicated by B, and the wire 79 with the group indicated by C. The wire 79 is here shown as of an anomalous nature and will be described in detail hereafter. Other groups D and E are also shown, group 10 D being connected in series with group C and group E being connected in series with group A. Likewise certain cross connections between the groups have been provided for which will be explained later.

15 Let us suppose a single contact to be made at 72; a current flows through 66, 72, 76, relay 80 and connection 81 to one of the relay members 54^e. This member being in contact with 54^a, a current passes to 53^e, 53^a, 20 and thence by way of the connection 53^x to relay 53 whence it returns to the battery via branch 83 and negative main 84. The relay being energized by this rush of current, the armature is attracted, making contact at 25 53^a—53^c, and 53^e—53^f, breaking contact at 53^b—53^c, and 53^a—53^e. This, therefore, breaks the circuit through the contact 72, but in place thereof current flows from the positive main 66 through the branch 85, connection 86, armature 87^a and connection 88 to the spring 54^e, whence it flows to 54^b, 53^c, 53^a, and lamp 53^l, thence passing through the relay 53 and back to the battery as before. The lamp 53^l, being illuminated, signifies that one impulse has been received over the wire 76 and this illumination continues so long as the contact 53^a—53^c is continued. Of course it will be obvious that other annunciating devices than the lamp 53^l 30 could be employed, a lamp being illustrated herein entirely because of the ease with which it may be shown. Also it will be obvious that this current which illuminates the lamp may be employed to effect further connections, or that further connections may be superposed upon the spring pile of the relay itself, such capability being so obvious as to require no extended mention.

Assuming the contact 72 to have been 35 made only momentarily, as it ordinarily would be, it is meanwhile returned to open position ready to record another impulse. Supposing this contact to be again closed so as to transmit over the wire 76 another impulse, this impulse will flow through 80, 81, 54^e, 54^a, 53^e, 53^f, 54^x, relay 54 and branch 83 to the battery. This serves to make contact at 54^a—54^c and 54^e—54^f, breaking contact at 54^b—54^c, and 54^a—54^e. Accordingly current ceases to flow through contact 72, but 40 flows through 66, 85, 86, 87^a, 88, 54^c, 54^a, 54^f, relay 54, and branch 83 back to the battery. Illumination of the lamp 54^l indicates the fact that two impulses have been received over the wire 76, while the breaking

of the contact at 54^b—54^c extinguishes the light at 53^l. It will be noted that in each case the first actuation of each magnet is effected by means of the current produced through the wire 76, and that the consequent attraction of the armature effects a contact at a—c, whereupon the sustaining current is derived from another circuit, the circuit through the wire 76 being broken immediately thereafter. However it will be seen 45 that the current through the sustaining circuit necessarily begins to flow before the original circuit is broken; also it will be seen that the contact through this sustaining circuit is closed before the preceding relay is released, wherefore all danger of the system becoming tied up is avoided.

In the present instance only two relays have been shown in group A, although it will be obvious that the number could be 50 extended as much as desired. The last relay of the group having been energized, let us suppose that the contact 72 is made once more, in this case a third time; the current flows through 66, 72, 76, 80, 81, 54^e, 54^f, 54^x, 85 and connection 90 to the relay 87. Thence it flows by way of connection 91 to 62^e, 62^a, 61^e, 61^a, and 61^x to the relay 61, and thence back to the battery by way of the branch 92. The energizing of the relay 87 55 opens the sustaining circuit at 87^a, deenergizing the relay 54 and extinguishing the lamp 54^l. Simultaneously the energizing of the relay 61 establishes contact at 61^a—61^e, and 61^e—61^f. Current now flows through 60 other positive mains 66, branch 93, and connections 63^c, 63^b, 62^e, 62^b, 61^e, 61^a, to the lamp 61^l and relay 61, returning to the battery via lead 92. The illumination of this lamp indicates that group A has been 65 once filled and run over, while the clearing of the group A has left it in condition for a new start upon the making of another contact. It will be obvious that the lamp 61^l is shown merely as a type and that an 70 annunciating device, contact making device, or other mechanical signal could be employed in its stead, or that the movement of the relay armature could be employed to effect yet other connections in addition 75 to those herein mentioned.

Reference has already been made to a relay 80 which is in series with the contact 72. While it is clear that only a momentary contact at 72 will be required to energize the relay next in turn and cause it to attract its armature so as thereafter to become sustained through another circuit, it will take only a moment's reflection to observe that if the contact 72 be held closed 80 for any extended time, the various relays will be actuated successively as rapidly as their armatures can be attracted so as to change the relation of their contacts. Thus if the contact 72 were accidentally held 85

closed without other provision the various relays of group A would be energized successively time after time without intermission. The control relay 80 is designed to 5 counteract this and to that end is provided with an armature connection 80^a adapted, upon the energizing of the relay, to make contact between the connection 81 and the return branch 84, thus shunting a part of 10 the circuit. Inasmuch as the armatures of the various relays move at about the same speed, the necessary changes in contact will be made at the receiving relays before the completion of the shunt at the control relay. The operation of the armatures can 15 be accelerated or retarded by changing the hysteresis and spring tension as will be well understood.

Next considering group B, it will be clear 20 upon inspection that the arrangement and mode of operation of the relays is exactly the same as in the case of group A wherefore extended explanation of the group itself is believed to be unnecessary. Likewise it will 25 be obvious that the number of relays in the group may be diminished or increased at pleasure. The last relay of this group is connected by way of its spring finger *f* and the lead 99 to the releasing relay 87. In 30 this case this releasing relay is shown as a double magnet identical with the releasing relay for group A although it is obvious that other arrangements could be employed. From this releasing relay the current passes 35 by way of 100, 57^e, 57^d, 56^e, 56^d, 55^e, 55^d, 55^x, to relay 55, and thence back to the battery via branch 101, main 70 and connections 68^b. This causes the establishment of contacts at 55^a—55^c, and 55^e—55^f, breaking contact at 55^b—55^c, and 55^d—55^e, after which 40 current flows through 66, 103, 55^e, 55^a, 55^x, 55, 101, 70, and 69^b. The lamp, (or other annunciator) being energized may be considered as giving any indication which convention 45 may have applied thereto, while the energizing of the relay 87 due to the passage of the current therethrough breaks the contact at 87^a and extinguishes the last lamp in group B.

50 By following out the contacts made at 74, it will be seen that a closing of the circuit at this point would cause a flow through 78, control relay 102, releasing relay 87, and thence by way of the connection 100 with 55 the various relays of group C, thus affording exactly the same indication as though an excess of impulses had been transmitted by way of group B. The control relay 102 is employed from the fact that an extended 60 contact at 74 might otherwise cause an incorrect signal, while the presence of the control relay would in such a case effect a short circuit at the point 102^a thus preventing the repeated actuation. Also it will be noticed 65 that the current from the contact 74 passes

through the releasing relay 87 thereby clearing all relays in groups A and B. Either or both of these expedients could be omitted, if desired, without invention or the releasing relay could be associated with 70 only one of the prior groups if necessary.

Supposing that after the actuation of the relay 55 in group C, a second impulse should be received over the connection 100 (either by way of the contact 74 or an overflow 75 from group B). The path taken by the current will be 100, 57^e, 57^d, 56^e, 56^d, 55^e, 55^f, 55^x, relay 56, 101, 70, 68^b, thus actuating the relay 56 and causing the changing of contacts heretofore explained. This, however, will 80 not, with the arrangement shown deenergize the relay 55, since in group C the fingers *c* are connected parallel with the positive main instead of being connected in series with the springs *B* of preceding relays. 85 Accordingly these indicators or annunciations remain energized after once having been actuated until a higher portion of the system is actuated to restrict them.

Supposing that all of the indicators of 90 group C are actuated, a succeeding actuation received through the connection 100 will be transferred directly to the connection 106 whence it will pass to 59^e, 59^d, 58^e, 58^d, 58^x, 58, 107, 70, and 68^b. The relay 58 95 being exactly the same as heretofore described, the same operations will take place, the lamp (or other device) *l* being actuated and sustained by reason of the sustaining circuit through the branch 105. Thus it will be seen that the different groups are arranged in progressive orders, A and B being of the lowest order, C and E being of the next higher order (inasmuch as they receive all or certain of their impulses from 100 orders below), and D being of a still higher order since it receives its impulses from the group C. Obviously these different groups could be extended to any length desired, or could be connected to themselves and to 110 each other by any of the modes disclosed herein. There is, however, an anomalous or emergency section of the apparatus here shown which should be considered, this portion of the circuit being in the present instance connected with the second relay of 115 group C, although many other possible connections will suggest themselves. In this case an additional contact member *m* is provided having fixed contacts upon sides 120 *n* and *o*, the contact *n* being connected by means of the lead 110 to the wire 78, and the contact *o* being connected by the lead 111 with the relay 112 which we here term the "emergency" relay. During the unexcited 125 condition of the magnet 56, the contacts *m*—*n* are closed so that an impulse received over the wire 79 passes into the relay 102 and then the relay 87, and thence into the group C like any impulse originating at 130

180

the contact 74. However, if the magnet 56 is energized previous to the currents of this contact the impulse will pass through 79, 56^m, 56°, 111, 112, 113, 70, and 68^b to the battery. This impulse will energize 5 the magnet 112, closing the contacts *a* and *b*, whereupon current will flow through 66, 85, 114, 115, 112^a, 112, and 113 to the battery as before. The lamp or other annunciator is 10 here shown in parallel with the magnet 112 so as to become energized simultaneously therewith. At the same time the closing of the contact *B* short-circuits the relay 68 (via 116, 117, 112^b, 113, and 70) permitting 15 the breaking of the contacts 68^a and 68^b whereupon the apparatus here shown becomes entirely inoperative until the insertion of another coin, or other suitable expedient, to effect the contact at 67^a. A 20 gong having a magnet 114 is shown in the connection 115 so that upon the actuation of the emergency relay an audible signal will be given.

It will be obvious that the coin mechanism could be omitted without effect upon the rest of the circuit, and that the coin controlling mechanism is capable of use in a great many locations which will suggest themselves to those skilled in the art; of 25 which gas and electricity meters, time locks, vending machines, game apparatus, and pre-payment telephones may be cited as examples. Also it will be apparent that within the operation of the rest of this mechanism other contact controlling means might be employed and governed or operated by other expedients than the dropping of the coin. It will also be apparent that the 30 emergency circuit 79, 111, etc. could be omitted entirely without reference to the rest of the system. Also it will be obvious that the contact 75 could be connected directly to the relay 112, but that connection is so obvious that illustration has not been 35 thought necessary and the present illustration has been selected inasmuch as it shows a mode of causing the signal received from this circuit to depend upon the prior condition of the receiving mechanism.

40 While we have described in detail the relay of our invention and pointed out at length certain forms of connection which may be employed we have done so solely with the idea of making plain our invention 45 and not for the purpose of limiting ourselves to the particular construction or arrangement herein set forth. Also while we have illustrated our improvements as combined in an extensive, complete, and 50 complicated system, it should be understood that our improvements relate to the component parts of that system as well as to the whole. Accordingly we do not confine ourselves to the arrangement or constructions herein described except as the same 55

may be included positively in the claims hereto annexed or may be rendered necessary by the prior state of the art.

Having thus described our invention, what we claim is:—

1. In electrical signaling mechanism, the combination, with contacts and a source of electric energy in circuit therewith, of signaling devices for said circuits, means for actuating said signaling devices successively 70 upon the repeated closing of said contacts, means for terminating the actuation of each signaling device upon the actuation of the next succeeding device, and means operative after a predetermined number of such actuations to produce an actuation of an annunciator of another series. 75

2. In electrical signaling apparatus, the combination, with an electrical contact and a source of electric energy connected therewith, of a series of signaling devices, means operative upon the closing of said contact for actuating the first signaling device of 80 said series, and means operative upon the second closing of said contact for actuating 85 the second signaling device of said series and simultaneously terminating the actuation of the preceding signaling device. 90

3. In electrical signaling apparatus, the combination with a plurality of electrical 95 contacts and a source of electric energy, of separate circuits connecting said source with said contacts, a series of signaling devices for each of said circuits, other series of signaling devices following certain of 100 said first series, means operative upon the repeated closing of any one of said contacts for actuating successively the signaling devices of the corresponding series, and means operative after the actuation of a predetermined number of devices of one of said first 105 series for effecting the actuation of a signaling device in said second series. 110

4. In electrical signaling mechanism, the combination, with a plurality of independently actuatable electrical contacts and a source of electric energy, of a plurality of separate circuits connecting said source with said contacts, a series of signaling devices for each of said circuits, means operative 115 upon the repeated closing of any one of said contacts for causing the successive actuation of the signaling devices of the corresponding series, and means operative upon the actuation of the last signaling device in any 120 series for causing the actuation of the next succeeding signaling device in another series. 125

5. In electrical signaling mechanism, the combination with a plurality of independently actuatable electrical contacts and a source of electric energy, of a plurality of separate circuits connecting said series with said contacts, a series of signaling devices for each of said circuits, certain of said se- 130

- ries being of a higher order than other series, means operative upon the repeated closing of any one of said contacts for causing the successive actuation of the signaling devices 5 of the corresponding series, means operative upon the actuation of any signaling device for terminating the actuation of the preceding device in its own series, and means operative upon the actuation of the last signaling device in any series of a lower order 10 for causing the actuation of the next succeeding signaling device in the corresponding series of the higher order.
6. In signaling apparatus, the combination, with a plurality of independently actuatable electrical contacts and a source of electric energy, of a plurality of separate circuits connecting said source with said contacts, a series of signaling devices for 15 each of said circuits, and forming groups of a first order, a higher series of signaling devices for each of said first series and forming groups of a higher order, means operative upon the repeated closing of said contacts for causing the successive actuation of the signaling devices of the corresponding lower series, means operative upon the actuation of the last signaling device of any lower series for causing the actuation of a 20 signaling device in the corresponding higher series, and means operative upon the actuation of a signaling device in any higher series for terminating the actuation of the devices in every lower series.
- 25 7. In signaling apparatus, the combination with a plurality of independently actuatable electrical contacts and a source of electric energy, of a plurality of separate circuits connecting said source with said contacts, a series of signaling devices for 30 each of said circuits, certain of said series being of a lower order and others being of a higher order, means operative upon the closing of any one of said contacts for causing the actuation of the signaling device next in order in the corresponding series, electrical connections between the last signaling device of each lower series and the circuit of one of said higher series, whereby 35 upon the actuation of the last device of such lower series the device next in order in the corresponding higher series will be actuated, and means operative upon the actuation of a device in any higher series by accumulation from any lower series for terminating all actuation in every lower series.
- 40 8. In signaling apparatus, the combination, with a contact device and a source of electric energy in circuit therewith, of a plurality of interlocking relays, means carried by each relay adapted, upon actuation of that relay, to connect said source and contact in series with the magnet of the succeeding relay so as to enable it to be actuated 45 upon the next actuation of said contact de-
- vice, an independent circuit between said source and said relays, means operative upon the actuation of any relay for closing said independent circuit through the magnet of said relay, and means carried by succeeding relays and adapted, upon actuation of those relays, to break said independent circuit and terminate the operation of the preceding relay.
9. In a signaling mechanism, the combination, with a contact device and a source of electric energy in circuit therewith, of a relay connected in said circuit and having a plurality of armature controlled contacts, an independent circuit connecting said relay with said source through certain of said contacts whereby upon the energizing of the relay magnet said independent circuit will be closed to maintain such energization, and means operative upon the occurrence of a predetermined event for breaking said independent circuit whereby said magnet is deenergized.
- 75 10. In signaling mechanism, the combination, with a contact device and a source of electric energy in circuit therewith, of a relay connected in said circuit and having a plurality of armature controlled contacts, an independent circuit connecting said relay with said source through certain of said contacts whereby upon the energizing of the relay magnet said independent circuit will be closed to maintain such energization, additional circuits connected with other of said contacts, and means operative upon the occurrence of a predetermined event for deenergizing said magnet whereby there is 80 permitted a shift in the arrangement of said additional circuits.
- 85 11. In signaling mechanism, the combination, with a contact device and a source of electric energy in circuit therewith, of a relay connected in said circuit and having a plurality of armature controlled contacts, an independent circuit connecting said relay with said source through certain of said contacts whereby upon the energizing of the relay magnet said independent circuit will be closed to maintain such energization, additional signaling devices connected in said independent circuit and adapted to be actuated by the passage of a current therethrough, and means operative upon the occurrence of a predetermined event for deenergizing said magnet whereby 90 the breaking of said secondary circuit is effected.
- 100 12. In signaling mechanism, the combination, with a contact device and a source of electric energy in circuit therewith, of a relay connected in said circuit and having a plurality of armature controlled contacts, certain of said contacts being arranged to be closed upon the attraction of said armature and others to be broken, an independent 105
- 110
- 115
- 120
- 125
- 130

circuit connecting said source and relay magnet in series through those armature contacts which are closed upon the energizing of said magnet, and means independent of said first named contact device for breaking said secondary circuit upon the occurrence of a predetermined event.

13. In signaling mechanism, the combination, with a contact device and a plurality of relays, each of said relays comprising a magnet, an armature, and a plurality of armature controlled contacts, certain of said contacts being arranged to be closed upon the attraction of said armature and others to be opened, of a circuit connecting said contact device with said source and passing through the magnet of the first relay and certain of its own normally closed contacts and the similar contacts of succeeding relays, a secondary circuit connecting said source with the magnet of said first relay and including a normally open contact of said first relay and normally closed contacts of said succeeding relays, and connections whereby upon the energizing of any relay said secondary circuit will be diverted to itself from the preceding relay and said first named contact device will be connected in series with the magnet of the succeeding relay.

14. In signaling mechanism, the combination, with a contact device and a source of electric energy in circuit therewith, of a relay in said circuit and adapted to be actuated upon the closing of said contact, an independent circuit connected through said source and the magnet of said relay and adapted to be completed upon the actuation of said relay so as to continue the operation of the same, and means for breaking said independent circuit upon the occurrence of a subsequent event in the operation of said mechanism, whereby said relay may be permitted to retake its former condition.

15. In signaling mechanism, the combination, with a contact device and a source of electric energy in circuit therewith, of a plurality of interlocking relays, means carried by each relay adapted, upon actuation of that relay, to connect said source and contact in series with the magnet of the succeeding relay, and a controlling relay in circuit with said source and contact and adapted, when actuated, to short circuit said first relays, the lag of said controlling relay being substantially the same as that of said first relays.

16. In signaling mechanism, the combination, with a contact device and a source of electric energy in circuit therewith, of a plurality of relays arranged in series and each having a plurality of armature controlled contacts, certain of said contacts being arranged, upon actuation of that relay, to connect said source and contact in series

with the magnet of the succeeding relay, other of said contacts being arranged upon the actuation of that relay to connect the magnet of that relay with said source through an independent circuit, and still other of said contacts being arranged, upon the actuation of that relay to open the independent circuit through the magnet of the preceding relay.

17. In signaling mechanism, the combination, with a plurality of normally open contacts and a source of electric energy in circuit with each of the same, of a succession of interlocking relays for each of said contacts, means carried by each relay adapted, upon actuation of that relay, to connect said source and contact in series with the magnet of the succeeding relay, an independent circuit between said source and said relays, means operative upon the actuation of any relay for closing said independent circuit through the magnet of that relay, a totalizing relay connected to the last of each of said first series of relays, and a circuit breaking relay having its magnet in series with each of said totalizing relays and its contacts in series with each of said independent circuits.

18. In signaling apparatus the combination, with an electro-magnet and an armature associated therewith, of a plurality of conducting members adjacent to said armature, certain of said conducting members being in contact with each other when said armature is retracted and others being in contact with each other when said armature is attracted, a normally open contact, a source of electric energy, a circuit connecting said source to said electromagnet by way of said contact, whereby said armature will be attracted upon the closing of the same, a separate circuit connected between said source and said magnet by way of a pair of said conducting members which are connected only when said armature is attracted, and an announcing device in said last circuit.

19. In signaling apparatus, the combination, with a series of normally unexcited electro-magnets, of a plurality of conducting members adjacent to each of the same, certain of said members being in contact with each other only when the corresponding magnet is unexcited and others being in contact only when such magnet is excited, a source of electric energy, a circuit connecting said source with one of said magnets, said circuit being by way of certain normally contacting conducting members of the succeeding magnets and also having a normally open contact, a separate circuit connected between said source and said magnet by way of other normally contacting members of the succeeding magnets, said separate circuit including a pair of normally sepa-

rated members in the magnet to which it is connected, and signaling means included with each magnet in said last named circuit, whereby said signaling means will be actuated successively upon the repeated closing of said normally open contact, and whereby each signaling device will be released upon the actuation of the succeeding magnet.

20. In a signaling apparatus, the combination with a source of electric energy and a normally open contact, of a series of relays, each comprising an electro-magnet and a plurality of conducting members *a*, *b*, *c*, *d*, *e*, *f*, of which *b*—*c* and *d*—*e* are in contact only when the corresponding magnet is unexcited while *a*—*c* and *e*—*f* are in contact only when the magnet is excited, an actuating circuit connecting said source with one terminal of each magnet and with both terminals of the first relay magnet, said actuating circuit containing said open contact and the members *d*—*e* of each relay, a sustaining circuit connecting said source with one terminal of each magnet and containing the members *b*—*c* of each relay, an annunciating device connected between the member *a* and the terminal of each magnet, and a connection between the terminal of each magnet after the first and the member *f* of the preceding relay.

21. In coin control mechanism for apparatus, the combination, with a coin chute and a normally open electric contact adjacent thereto and adapted to be closed temporarily upon the passage of a coin of predetermined size, of a source of electric energy, an electro-magnet, a circuit connecting said source and magnet and including said contact, means operative upon the energizing of said magnet for shunting said open contact and for simultaneously rendering said apparatus available, and means operative after the occurrence of a predetermined number of events for deenergizing said magnet whereby said shunt will be broken and said apparatus rendered unavailable.

22. In coin control mechanism for apparatus, the combination, with a source of electric energy and a normally open contact adapted to be closed momentarily by the deposit of a coin, of an electro-magnet, a circuit connecting said magnet with said battery and including said open contact, an annunciating device in said circuit, means operative upon the energizing of said magnet for shunting said open contact, means operative upon the energizing of said magnet for rendering said apparatus available, and means operative after a predetermined number of events for deenergizing said magnet whereby said shunt will be broken and said apparatus rendered unavailable.

23. In coin control mechanism for apparatus, the combination with a source of electric energy and a normally open con-

tact adapted to be closed momentarily by the deposit of a coin, of an electro-magnet, a circuit connecting said magnet with said battery and including said open contact, armature contacts adapted, upon the excitation of said magnet, to shunt said coin contact, other armature contacts adapted, upon the excitation of said magnet, to render available the apparatus controlled thereby, and means governed by said apparatus for short circuiting said magnet, whereby the separation of said first armature contacts is permitted and said magnet deenergized.

24. In apparatus of the character described, the combination, with a source of electric energy and signaling mechanism operative upon the occurrence of different events, of an electro-magnet having an armature, means operative upon the attraction of said armature for rendering said signaling mechanism operative, a normally open contact, means operative upon the temporary closing of said contact for connecting said source through said magnet, means operative upon the energizing of said magnet for maintaining the energization of said magnet, and means operative upon the establishment of a predetermined connection in said signaling apparatus for deenergizing said magnet.

25. In signaling apparatus, the combination, with a plurality of normally open electric contacts and a source of electric energy, of a plurality of signaling devices connected in series with each of said contacts and adapted to be operated in succession upon repeated closings of the corresponding contact, an emergency circuit, and means operative upon the occurrence of an impulse in said emergency circuit for resetting all of said signaling devices.

26. In signaling apparatus, the combination, with a plurality of normally open contacts and a source of electric energy, certain of said contacts being connected in series with a plurality of signaling devices so arranged as to be actuated successively upon repeated actuations of said contacts and other of said contacts being connected to an emergency circuit, of an electro-magnet having an armature, an independent circuit through said magnet whereby the same may be energized and said armature attracted, means operative upon the attraction of said armature for producing a sustaining current through said magnet, an annunciating device in said emergency circuit and operative upon the occurrence of an impulse therein, a plurality of annunciating devices for each of said other circuits, means for actuating successively the devices in each circuit upon repeated closings of the contact in that circuit, all of said circuits passing through contacts carried by said armature, and means operative upon the

occurrence of an impulse in such emergency circuit for deenergizing said magnet and releasing said armature whereby said other circuits may be opened.

5 27. In signaling apparatus, the combination, with a plurality of normally open contacts, one of the same being an emergency contact, and others being signaling contacts, of a source of electric energy, an 10 electro-magnet having an armature, circuit devices controlled by said armature, a circuit from said source in series with each of said signaling contacts, annunciating devices in said circuits and adapted to be 15 actuated upon the closing of those contacts, and means operative upon the closing of said emergency contact for opening all of said circuits.

28. In signaling mechanism, the combination, with a plurality of normally open contacts and a source of electric energy in circuit with each of the same, of a primary group of relays for each of said contacts, means operative upon the actuation of any 25 relay to connect the corresponding contact in series with the magnet of the succeeding relay, an independent circuit between said source and said relays, means operative upon the actuation of any relay for closing 30 said independent circuit through the magnet of that relay, a secondary group of relays connected to the last relay of each primary group, and a circuit breaking relay having its contacts in series with the independent circuits of all of said first relays 35 and having an independent magnet winding in series between each secondary group and the last relay of each primary group.

29. In signaling apparatus, the combination, with a plurality of normally open

electric contacts and a source of electric energy in circuit with each of the same, of a plurality of relays for certain of said circuits and adapted to be operated successively upon repeated closing of the corresponding circuit, additional contact members carried by one of said relays and connected with another of said normally open contacts, and signaling devices connected to said additional contacts and adapted to be operated from said last named normally open contact only when said additional contacts are in a predetermined relation. 45

30. In signaling apparatus, the combination, with a plurality of normally open electric contacts and a source of electric energy in circuit with each of the same, of a plurality of relays for certain of said circuits and adapted to be operated successively upon repeated closing of the corresponding circuit, an additional contact member associated with one of said relays and arranged to assume different positions when that relay is energized and deenergized, said contact member being in circuit 60 with another of said normally open contacts, a group of signaling devices arranged in circuit with said additional contact member when its relay magnet is deenergized and other signaling devices arranged in circuit with said additional contact member 65 when that relay magnet is energized. 70

In testimony whereof we hereunto affix our signatures in the presence of two witnesses.
